RIGHT ANGLE HEAD WRENCH

James E. Fercana, North Jackson, Ohio

Application January 27, 1955, Serial No. 34,267

Term of patent 14 years

(Cl. D54—16)

Fig. 1 is a perspective view of a right angle head wrench, showing my new design;

Fig. 2 is a top plan view thereof;

Fig. 3 is a side view thereof; and

Fig. 4 is an end view thereof.

The back side of the right angle head wrench is a duplicate of the side shown in Figs. 1 and 2.

I claim:

The ornamental design for a right angle head wrench, as shown and described.
